UNITED STATES PATENT OFFICE

2,441,062

WIND WHIP DRYING APPARATUS

Otto Elsebusch, Los Angeles, Calif.

Continuation of application Serial No. 580,535,
March 2, 1945. This application February 17,
1948, Serial No. 8,817.

5 Claims. (Cl. 34—106)

1

This invention relates to a wind whip drying apparatus.

An object of the invention is the construction of an efficient and novel apparatus for the drying of clothes.

Another object of the invention is the construction of a novel drying apparatus whereby steam is saved during the operation thereof.

A further object of the invention is the construction of an efficient and novel apparatus, including the construction of the casing and its associated parts, as well as the means for suspending or supporting the garment upon the apparatus.

This is a true copy of my original case, Serial No. 580,535, filed March 2, 1945, and allowed July 8, 1947. The case expired on January 8, 1948, containing the five (5) claims of this application.

With the foregoing and other objects in view, my invention comprises certain novel constructions, combinations, and arrangements of parts as will be hereinafter fully described, illustrated in the accompanying drawings, and more particularly pointed out in the appended claims.

In the drawings:

Figure 1 is a view in elevation of an apparatus constructed in accordance with the present invention.

Figure 2 is an enlarged vertical, central sectional view of the apparatus.

Figure 3 is a horizontal sectional view taken on line 3—3, Figure 2, and looking in the direction of the arrows.

Figure 4 is a horizontal sectional view taken on line 4—4, Figure 2, and looking in the direction of the arrows.

Figure 5 is an enlarged fragmentary, vertical sectional view of the apparatus showing the same holding a garment.

Figure 6 is an enlarged vertical sectional view of a portion of the garment support.

Figure 7 is a fragmentary view in elevation of the apparatus, showing the upper section of the sectional casing in position.

Referring to the drawings in which I have shown the preferred embodiment of my invention, in Figure 7, 1 designates the lower or primary section of the casing and 2 (Fig. 7) designates the upper section of the casing. The lower section 1 is closed at its bottom and is provided with angle feet 3. Above the closed bottom is a wire mesh 4 which permits air to enter and pass around the steam pipes 5. The steam pipes 5 are provided with a suitable inlet and outlet. A horizontal bracket 6 is secured to the inner face of the casing 1 and supports a motor 7. The fan 8 of motor 7, when in motion, draws the air from around the steam pipes 5, which results in saving steam, as it is more expensive to blow the

2

air over coils or steam pipes. Around motor 7 is a shield 9 to prevent heating of the motor by the hot air passing upward from around the pipes or coils. A vent pipe 10 is provided directly under the motor 7; this pipe opens through the closed bottom to the outer atmosphere, whereby cool air is discharged against the bottom and up and around the motor.

A safety screen 11 is placed in the casing 1 near its upper end (Fig. 2) and under this screen are vertically positioned deflector plates 12.

A steam pipe 13 projects into the casing 1 and on its discharge end is a deflector 14. The purpose of this device is to fluff up velvets or to bring out nap on some garments when installed upon the apparatus, per Fig. 1.

Around the top of casing 1 is a rubber band or belt 15. This band projects above the top edge of the casing or section 1 so that it can receive the upper section 2, as may be seen upon referring to Figure 7. This band 15 performs the dual function of receiving and holding the upper section 2 in a seated sealed position, as well as forming a gripping surface for the garment.

25 A plurality of clamping devices are attached to the side of the lower or primary section of the casing, and each clamping device comprises a bracket 16 on which is pivotally mounted a curved arm 17. An angle grip 18 is secured to the upper end of arm 17, and on the inner face of the arm is a rubber pad or unit 19; this pad registers with the rubber band 15. The garment 20 (Fig. 1) is placed between band 15 and the rubber pads 19 of the clamping devices, and 30 then the clamping devices are permitted to close upon the garment, whereby it is securely held in place. A coil spring 21 is fastened in eye 22 of the arm 17 (Fig. 5), and the lower end is fastened in eye 23 formed on bracket 16.

35 When the upper section 2 of the casing is in position, Fig. 7, there will be two sets of clamping devices in use, the upper set cooperating with the upper rubber band 15a, the same as the lower set cooperates with the lower rubber band 15. The clamping devices are all of similar construction, as hereinbefore described.

The garment supporting device of the apparatus comprises a hollow cylinder or pipe 24 which has its lower end supported by one of the angle feet 3, and a band 25 surrounds pipe 24 and assists in securing it to the casing 1. A rod 26 is slidably mounted in pipe 24, and the rod is provided with a head 27 on its inner end. A lock bolt 28 extends into the pipe 24, 50 in the path of the head 27 to prevent the rod from being too far drawn upward, thereby preventing the rod from being removed from pipe 24. The rod 26 is provided on its outer end with a hook 26a, Fig. 1. A clamp device is provided on the upper end of pipe 24 for holding the rod 26 in

adjusted positions. This clamp device comprises a primary jaw 29 that is attached at its lower end to the side of pipe 24. An auxiliary jaw 30 has its inner end in a socket portion 31 of jaw 29. The rod 26 extends through the primary jaw 29 and auxiliary jaw 30. A coil spring 32 is on rod 26 between jaws 29 and 30. Therefore, when the jaws are in their normal position they clamp upon the sides of rod 26 holding the same in an adjusted position, but when the operator presses inwardly on the outer ends of the jaws this releases them from their gripping position on rod 26, permitting said rod to be vertically adjusted, to accommodate different sizes and lengths of garments.

Any suitable coat hanger may be used for suspending the garment on hook 26a (Fig. 1).

The air passes upwardly through the apparatus in a rolling condition, by reason of striking against the fins or deflector plates 12.

The upper section 2 of the sectional casing is used for smaller garments.

It is to be noted that by reason of the solid bottom of the casing, no dust nor dirt, nor lint will be sucked off the floor and plug up the coils of the steam pipe or pipes.

It is to be understood that the motor 1 is supplied with electric current in any common manner and that the inlet and outlet for the coils or pipes 5 are of any standard construction suitable for the efficient functioning of this apparatus. Further, steam passing to and through pipe 13 can also be controlled in any common way.

While I have described the preferred embodiment of my invention and illustrated the same in the accompanying drawings, certain minor changes or alterations may appear to one skilled in the art to which this invention relates during the extensive manufacture of the same, and I, therefore, reserve the right to make such alterations or changes as shall fairly fall within the scope of the appended claims.

What I claim is:

1. In an apparatus of the class described, the combination of a hollow lower casing provided on its upper edge with a rubber band, said band extending above the upper edge a slight distance, an upper hollow casing placed on the upper edge of the lower casing with said rubber band partly engaging the upper casing, each of said casings having open ends, clamping devices provided with rubber pads on the outside of said lower casing, whereby said clamping devices can clamp the lower end of a hollow garment against said rubber band, and a fan and heating means within said first-mentioned casing, whereby heated air is circulated upwardly through the superposed casings into a garment supported thereover.

2. In an apparatus of the class described, the combination of a hollow casing, said casing provided with open ends, clamping devices on the outside of and near the upper end of said casing, each clamping device comprising a bracket having an upstanding eye, a curved arm pivoted at its lower end upon said bracket, an angle grip secured to the upper end of said arm, a rubber pad secured to the inner face of said arm at its upper edge, a coil spring fastened at its upper end to said arm near said rubber pad and fastened at its lower end in the upstanding eye of said bracket, said hollow casing provided with a rubber band on its outside and said band

registering with the rubber pads of said clamping devices, and a fan and heating means within said first-mentioned casing, whereby heated air is circulated upwardly through said casing into a garment supported thereover.

3. In an apparatus of the class described, the combination of a hollow sectional casing, the sections of said casing being open at their ends, said sections being positioned one above the other and having meeting ends, a rubber band engaging said sections over the meeting ends, a set of clamping devices fastened to the outer face of one section and cooperating with said rubber band to clamp a hollow garment superimposed thereover, and a fan and heating means within said sectional casing, whereby heated air is circulated upwardly through the sections of said casing into a garment supported thereover.

4. In an apparatus of the class described, a hollow casing composed of two tiered sections, said sections being open at both ends, one of said sections resting upon the other section, a rubber band over the contacting edges of said sections, clamping devices on one section contiguous to said rubber band, said clamping devices provided with rubber pads, said rubber pads and rubber band being adapted to hold a hollow garment therebetween, and a fan and heating means within said casing whereby heated air is circulated upwardly through the casing into a garment supported thereover.

5. In an apparatus of the class described, the combination of a hollow casing, clamping devices on the outside of said casing, said casing being open at both ends, each clamping device comprising a bracket having an upstanding eye between the outer ends of the bracket and said casing, a curved arm pivoted at its lower end upon said bracket and overhanging said eye, a grip projecting outwardly from said curved arm between its ends, a rubber pad secured only to the inner face of said curved arm, a coil spring fastened at its lower end to said eye and at its upper end to said curved arm under said rubber pad, said casing being provided with a rubber band entirely around its upper edge registering with the rubber pad on said curved arm, and a fan and heating means within said casing, whereby heated air is circulated upwardly through the casing into a garment supported thereover.
